CLAIM

The ornamental design for a roasting stick, as shown and described.

DESCRIPTION

FIG. 1 is a perspective view of a roasting stick showing our new design.

FIG. 2 is a top view of the roasting stick of FIG. 1.

FIG. 3 is a front view of the roasting stick of FIG. 1. The back view is a mirror image of the front view.

FIG. 4 is a bottom view of the roasting stick of FIG. 1.

FIG. 5 is a left end view of the roasting stick of FIG. 1; and, FIG. 6 is a right end view of the roasting stick of FIG. 1.

Broken lines are used to illustrate features of the roasting stick which form no part of the claimed design.

1 Claim, 2 Drawing Sheets
